HEAT SAVING SHIELD FOR WINDOWS

Isaac Goldmerstein, New York, N. Y.

Application February 8, 1943, Serial No. 475,105

13 Claims. (Cl. 160—354)

This invention relates to new and useful improvements in heat saving shields for windows.

The invention contemplates a new heat saving shield for a window, characterized by a stiff board such as cardboard, or other pasteboard, and other materials, adapted to extend across the inside dimensions of a window frame and formed with a back panel and flexibly connected side panels obliquely extending forward against the sides of a window frame and associated with a stiff strip adapted to be mounted across the window frame and to bear against the back panel for holding the board in position.

The new shield for windows is particularly intended to reduce the radiation of heat through the window and window panes, as a war emergency measure to save heat. Of course the new shields are opaque and may be used for blackouts.

Still further the invention proposes providing the edges of the stiff board with binding material which will assist in preventing or reducing the circulation of air around the shield.

The invention proposes various modified forms of shields, each of which embodies the essential features of this invention. In one form certain fastening elements are proposed for assisting in holding the stiff strip in position, which in turn holds the stiff board. In another form, different kinds of fastening means are proposed. In still another form it is contemplated constructing the stiff board of several sections either in the vertical or horizontal directions, such as a bottom section and a top section similar to the inner and outer sashes of a window.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a window viewed from the inside of a room and equipped with a heat saving shield in accordance with this invention.

Fig. 2 is a horizontal sectional view taken on the line 2—2 of Fig. 1.

Fig. 3 is a fragmentary enlarged detailed view of a portion of Fig. 2 disclosing particularly the binding and the edge of the stiff board.

Fig. 4 is an elevational view of the air shield in a collapsed condition.

Fig. 5 is a sectional view taken on the line 5—5 of Fig. 4.

Fig. 6 is a fragmentary elevational view of a window equipped with a heat saving shield constructed in accordance with a modified form of this invention.

Fig. 7 is a perspective view of the stiff strip used in Fig. 6.

Fig. 8 is an elevational view of a window provided with a heat saving shield constructed in accordance with still another form of this invention.

Fig. 9 is a horizontal sectional view taken on the line 9—9 of Fig. 8.

Fig. 10 is another elevational view of a window provided with an air shield constructed in accordance with still another form of this invention.

Fig. 11 is a vertical sectional view taken on the line 11—11 of Fig. 10.

Fig. 12 is a similar view to Fig. 9 in accordance with another modified form of the invention.

Figs. 13 to 17 are similar views to Fig. 3 but illustrating other modified forms of the invention.

Fig. 18 is a similar view to Fig. 5, illustrating another form of the invention.

In the form of the invention illustrated in Figs. 1—5 inclusive, the heat saving shield includes a stiff board 12 for extending across the inside dimensions of a window frame such as indicated by reference numeral 13. This stiff board 12 has a back panel 14 and flexibly connected side panels 15 obliquely extending forwards against the sides of the window frame 13. Preferably, the stiff board 12 is of cardboard, corrugated board, or other type of board. The panels 14 and 15 are formed by creasing or folding the material forming the board.

A stiff strip 16 is adapted to be mounted across the window frame 13 and to bear against the back panel 14 for holding said board in position.

This strip 16 may be constructed from a thin strip of wood. Fastening elements are provided for holding the strip 16 as desired. As disclosed, this fastening means includes a fastening element 18 connected between the center of the strip 16 and the center of the board 12. Thus, the strip 16 is not only connected with and supported on the board 12, but it may pivot to a vertical position, as for example shown in Figs. 4 and 5. However, the strip 16 may also be sold unattached.

The window frame 13 is provided with pins 19 or other abutment behind which the ends of the strip 16 are engaged. Thus, the strip 16 squeezing against the back panel 14 holds the

board in position. The resiliency of the connection between the panels 14 and 15 is dependent upon to cooperate with the strip 16 to hold the board. Another pin 19 is driven into the base portion of the window frame 13 and engages against the bottom of the board 12, assisting in holding it in position.

Binding strips 20 are attached to the edges of the board 12. Preferably, these binding strips are of cloth or other soft material. They are attached by lines of stitches 21, or in any other way. They engage against the window frame 13 and serve to reduce the circulation of heat and air through the window. When the air shield is not in use it may be folded as illustrated in Figs. 4 and 5 and stored away.

In Figs. 6 and 7 a modified form of the invention has been disclosed which is similar to the prior form, distinguishing merely in the way in which the stiff strip 16 is supported. In this form of the invention one end of the stiff strip 16 is pivotally connected by a pintle 22 with a fastening element 23 mounted on the side of the window frame. The other end of the strip 16 engages behind a pin 24. Another pin 25 is mounted on and projects from the strip 16 and rests upon and is supported by the pin 24. With this construction the strip 16 may be pivoted to an open position about the pivot 22.

In Figs. 8 and 9 another modified form of the invention has been disclosed which is very similar to the first form, distinguishing merely in the fact that the stiff board 12' is constructed with a plurality of panels 14', 15' and 15''. These panels are formed with openings 14^b and 14^d, covered by suitable transparent sheets 14^a and 14^c, respectively so that light may penetrate through openings 14^b and 14^d without allowing any air to pass through the same. These panels are also formed by additional vertical creases extending along the height of the stiff board. With this construction it is possible to fold the air shield to a smaller compass when it is not being used.

In Figs. 10 and 11 still another modified form of the invention is disclosed which primarily distinguishes from the prior form in the fact that the air shield includes a stiff board 12'' formed from two sections. There is a top section 28 and a bottom section 29. These sections are releasably connected with each other by a staple 30 engaged through the overlapping adjacent edge portions. The top section 28 is supported in position by a strip 16 engaging against its back panel. This strip 16 is pivotally connected by a pintle 22 with a pin 23 mounted on the window frame. The strip 16 has another pin 25 resting on a pin 24 on the other side of the window frame. The bottom section 29 is illustrated supported in position by a stiff strip 16 which is pivotally mounted at its center by a pintle 18 upon the back panel of the section. The ends of the strip 16 engage behind pins 17 mounted on the sides of the window frame. In other respects this form of the invention is similar to the previous form.

In Fig. 12 the board 12'' is divided into two equal sides 15''' by the vertical central crease. In other respects this form of the invention is similar to the previous forms.

In Fig. 13 part of the binding strip 20^a is stitched within the edge of the panel 15. In Fig. 14 the binding strip 20^b is stitched at 21 to the side of the member 15.

In Figs. 15 and 16 the panel 15^a is illustrated

with a folded edge 15^b and the binding strip 20^d is shown to be fastened to the side of the panel 15^a by stitches 21. In Fig. 17 the panel 15^c is shown with a double fold 15^d and the binding strip 20^c is shown to be stitched at 21 to the side of the panel 15^c.

In Fig. 18 both side panels 15 are shown to be folded on one side of the back panel 14.

It is to be understood that this heat saving shield may be of any shape, size and material and that the retaining strip 16 may hold the heat saving shield in position without any holding pin, or by a string stretched between the sides of the window frame.

15 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

25 1. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position.

30 2. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, said stiff board being a cardboard or the like board.

35 3. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, said stiff strip being a strip of wood.

40 4. A heat saving shield for windows, comprising a stiff board for extending across the inside dimensions of a window frame and having a back panel and flexibly connected side panels obliquely extending forwards against the sides of the window frame, a stiff strip adapted to be mounted across said window frame and to bear against said back panel for holding said board in position, and binding material upon the edges of said stiff board.

45 5. A heat saving shield for windows, comprising a stiff board for extending across the inside dimensions of a window frame and having a back panel and flexibly connected side panels obliquely extending forwards against the sides of the window frame, a stiff strip adapted to be mounted across said window frame and to bear against said back panel for holding said board in position, and binding material upon the edges of said stiff board, said binding being cloth, and sewed in position.

50 6. A heat saving shield for windows, comprising a stiff board for extending across the inside

dimensions of a window frame and having a back panel and flexibly connected side panels obliquely extending forwards against the sides of the window frame, and a stiff strip adapted to be mounted across said window frame and to bear against said back panel for holding said board in position, and fastening elements for holding said stiff strip mounted across said window.

7. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, and fastening elements for holding said stiff strip mounted across said window, including a pivotal fastening element connecting the center of the strip with the center of said board.

8. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, and fastening elements for holding said stiff strip mounted across said window, including a pivotal fastening element connecting the center of the strip with the center of said board, and pins mounted on said window frame behind which the ends of said strip engage.

9. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, and fastening elements for holding said stiff strip mounted across said window, including a pivotal fastening element connecting the center of the strip with the center of said board, and pins mounted on said window frame behind which the ends of said strip engage, and another pin mounted on the bottom portion of

5 the window frame and engaging the bottom portion of said board.

10. A heat saving shield for windows, comprising a stiff board for extending across the inside dimensions of a window frame and having a back panel and flexibly connected side panels obliquely extending forwards against the sides of the window frame, a stiff strip adapted to be mounted across said window frame and to bear against said back panel for holding said board in position, and fastening elements for holding said strip comprising a pin for mounting on the side of the window frame and pivotally connected with said strip, and pins for supporting the other end of said strip.

11. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said panel for holding said board in position, said stiff board being made from a pair of sections having overlapping adjacent edge portions.

12. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said panel for holding said board in position, said stiff board being made from a pair of sections having overlapping adjacent edge portions, and means for releasably securing these edge portions together.

13. A heat saving shield for windows, comprising a stiff board for extending across the inside dimensions of a window frame and having a back panel and flexibly connected side panels obliquely extending forwards against the sides of the window frame, and a stiff strip adapted to be mounted across said window frame and to bear against said back panel for holding said board in position, said stiff board being provided with additional panels produced by folding.
